UNITED STATES PATENT OFFICE

JULIUS J. GOETZ, OF SHOREWOOD, WISCONSIN, ASSIGNOR TO WESTERN METAL SPECIALTY CO., OF MILWAUKEE, WISCONSIN, A CORPORATION OF WISCONSIN

HEATER

Application filed January 12, 1927. Serial No. 160,630.

REISSUED

This invention relates to improvements in heaters, and more particularly to a charcoal heater for freight cars and the like.

It is one of the objects of the present invention to provide a heater which, except for several small castings, is formed entirely of sheet metal.

A further object of the invention is to provide a heater of the class described in which the fire pot side is retained in place by the grate which is secured by bolts, the fire pot side being thereby readily removable for repairs or replacement.

A further object of the invention is to provide a heater of the class described in which sparks from the fuel cannot escape from the heater.

A further object of the invention is to provide a heater having means for regulating the feed from the hopper to the fire pot.

A further object of the invention is to provide a freight car heater equipped with a lighter adapted to hold inflammable substances for the purpose of igniting charcoal in the fire pot.

A further object of the invention is to provide a heater in which the cover for the fuel reservoir or hopper is air tight when in closed position.

A further object of the invention is to provide a heater of the class described which is of very simple construction, is strong and durable, is inexpensive to manufacture, is efficient in operation, and is well adapted for the purpose described.

With the above and other objects in view the invention consists of the improved heater, and its parts and combinations as set forth in the claim, and all equivalents thereof.

In the accompanying drawings in which the same reference characters indicate the same parts in all of the views:

Fig. 1 is a vertical sectional view of the improved heater;

Fig. 2 is a plan view thereof; and

Fig. 3 is a cross-sectional view taken on line 3—3 of Fig. 1.

Referring now more particularly to the drawings it will appear that the heater includes a cylindrically shaped shell or casing

8 formed of corrugated sheet metal and closed at its lower end portion by a bottom 9. Angular members 10 forming legs are riveted to an internal iron ring 10' which is bolted to the bottom portion of the shell.

The top of the shell is partially closed by a top member 11 whose edge portions are rolled or crimped into engagement with the rolled edge of the shell, as shown in Fig. 1. The top member is provided with a medial circular opening 12 of a substantial size. The edges of the top member adjacent the opening are flanged downwardly, as at 13. Said opening 12 is normally closed by a cover 14 having an air-tight engagement with the top member. As shown in Figs. 1 and 2, the cover is of a dished formation and is provided on its upper surface within the dished portion with a diametrically extending rib 15 of channel formation. A bar 16 overlies the top of the rib and is welded thereto and projects outwardly from the sides of the cover. The channelled rib, between the bar and cover, prevents distortion of and damage to the cover by the improper insertion of tools. The bar and rib are secured to the cover by rivets 17. The top member 11 is provided with a pair of oppositely disposed lugs 18, which, when the cover is positioned in the opening and turned, engage the projecting ends of the bar 16 to removably lock the cover in position. A chain 19 secured to the cover and to the top member prevents the top from being entirely removed from the heater and lost.

Positioned within the shell, approximately halfway between its extremities, is a downwardly and inwardly inclined funnel-shaped member 20 of sheet metal and forming a hopper. The upper edge portion of the hopper is riveted to the shell, while the lower edge portion of the hopper is crimped into engagement with a member 21 folded to form a slide track for a shut-off plate 22 which is horizontally slidably mounted between portions of the member 21 and is adapted to register with the open lower end portion 23 of the hopper to control the same.

The outer end portion of the shut-off plate 22 has hinged thereto an operating handle 24 which normally hangs in a vertical posi-

tion, as shown in Fig. 1, and is releasably held in this position by a lock 25. To operate the shut-off plate the handle 24 is moved to a horizontal position and then pushed inwardly or withdrawn to open or close the opening 23 by the plate 22, as the case may be. The shell is slotted, as at 26, to permit passage of the handle.

A circular throat member 27 is positioned 13 immediately below the opening 23 of the hopper and said throat member engages the flanged portion 28 of the member 21. The throat member 27 is surrounded by a cone deflector 29 which engages at its upper portion 15 the member 21 and at its lower portion it is crimped into engagement with the throat member, as at 30. Angle pieces 31 are riveted to the cone deflector and bolted to the shell and said angle pieces have secured thereto a 23 circumferential spark deflecting collar 32.

Also crimped at its upper edge portion with the lower portion of the throat member is an apertured, outwardly and downwardly inclined fire pot top member 33, of circular 25 formation. The lower portion of said fire pot top carries brackets 34 which hold bolts 35 which carry in spaced relation a conical grate member 36, the grate being held thereon by nuts 37. A circular, vertically positioned and apertured fire pot side 38 is disposed in a groove 39 in the grate and the upper edge portion of the fire pot side is overlapped by the fire pot top 33.

Below the fire pot and grate and resting on 25 an inner bottom member 40 is an ash pan 41 to receive ashes falling through the grate. Access to the ash pan is afforded by means of an opening 42 in the lower portion of the shell, normally closed by means of a vertically 40 slideable door 43 movable in a door runner 44. The door is normally held in closed position by a pivoted catch 45 adapted to engage a lug 46.

When the door is raised to open position, a 45 lighter 47, mounted on a pivotal, horizontal arm 48 may be moved outwardly through the door opening and when so moved the lighter will also serve to hold the door in open position. The lighter is adapted to contain readily inflammable material for the purpose of igniting fuel within the fire pot.

A chain 49, carrying a triangular toggle 50, is secured to the outer surface of the shell, and the same is used in handling the heater. 55 It should also be observed that the casing or shell, at desired place, is formed with a plurality of spaced apertures 51 to permit the escape of heat.

In use, fuel, preferably charcoal, is disposed 60 within the hopper of the heater and the fuel is automatically fed by gravity into the fire pot, the speed of feeding being controlled by the adjustable shut-off plate 22. Fuel in the fire-pot is ignited by means heretofore 65 explained and the ashes of the spent fuel

fall through the grate into the ash pan. Sparks from the fuel are deflected and arrested by the cone deflector 29 and the collar 32 and cannot escape from the shell. If the fire pot side at any time requires removal 70 for replacement or repairs, it can be readily removed by removing the nuts 37 and dropping the grate 36.

From the foregoing description it will be 75 seen that the improved freight car heater is of very simple and novel construction and is well adapted for the purposes described.

What I claim as my invention is:

In a heater, a sectional and readily detachable and removable fire pot comprising a 80 downwardly and outwardly inclined fire pot top, brackets carried by the lower periphery of said fire pot top, a conical grate member disposed below said fire pot top, said grate member having an annular grooved flange, 85 bolts extending from said brackets through said flange, and a circular, vertically positioned fire pot side having its lower edge disposed within the groove of said flange and supported by the grate member and overlapping at its upper edge portion the lower edge portion of said fire pot top.

In testimony whereof, I affix my signature.

JULIUS J. GOETZ.
